UNITED STATES PATENT OFFICE.

CHARLES M. STEIN, OF PARIS, FRANCE, ASSIGNOR TO SOCIETE ANONYME DES APPAREILS DE MANUTENTION ET FOURLS STEIN, OF PARIS, FRANCE, A CORPORATION OF FRANCE.

RECUPERATOR STRUCTURE.

Application filed July 26, 1922. Serial No. 577,572.

To all whom it may concern:

Be it known that I, CHARLES M. STEIN, a citizen of France, a resident of Paris, France, have invented a certain new and useful Recuperator Structure, of which the following is a specification.

The invention relates to a recuperator structure made up of tiles having vertical openings therein, and built up into parallel spaced columns whereby the above-mentioned openings provide substantially unrestricted vertical passages for the air or gas to be pre-heated, and the spaces between such vertical columns are utilized to provide conduits for the exhaust or waste gases which are to be led through the recuperator.

One object of the invention is to provide a recuperator structure of the above character wherein the column of tiles will be adequately braced or firmly held in position in a simple manner, and without interfering with the passage of the waste gases through the recuperator, or necessitating modifications in its general construction.

It is also desired to dispose such bracing or retaining members for the columns so with relation to the remaining elements of the recuperator as not to interfere with the operations of cleaning the same or regulating the passage of the waste gases therethrough.

Another object of the invention is to construct a recuperator of the above type in such manner as to permit efficient regulation therein of the flow of exhaust gases, preferably both in respect to the entire amount of draft, and to eliminate inequalities in the draft in different parts of the recuperator.

Further objects and advantages of the invention will be in part obvious and in part specifically pointed out in the description hereinafter contained, which, taken in connection with the accompanying drawings, discloses a preferred embodiment thereof; such embodiment, however, is to be considered merely as illustrative of its principle. In the drawings:

Fig. 1 is a vertical section of a recuperator made in accordance with the invention.

Fig. 2 is a horizontal section taken on line 2—2 of Fig. 1, looking in the direction of the arrows.

Referring to the drawings, the recuperator is shown as embodying a plurality of

tiles 1 built up into a plurality of parallel spaced vertical columns 2, the tiles of each column having aligned vertical passages 3 leading upwardly from the bottom of the recuperator, whereby the air or gas to be preheated may enter the passages 3 aforesaid from the intake chamber 4 at the bottom of the recuperator, and pass upwardly through such passages to a gathering chamber 5 at the top of the recuperator from whence the preheated air or gas is suitably led to its desired point of utilization, for example, by a passageway 6.

A plurality of substantially horizontal plates 7 are interposed at various levels between the adjacent columns 2 of tiles, thus providing a plurality of conduits 8 extending across the recuperator from side to side, and which serve to conduct the waste gases into intimate contact with the tiles, as well as to provide lateral bracing between adjacent columns and assist in closing the horizontal joints between tiles at different levels.

The exhaust or waste gases are led to the recuperator in any suitable manner, for example, through an intake flue 9, from which the waste gas passes into a chamber 10 at one side of the above-mentioned spaced columns of tiles, and through the horizontal conduits 8 to a similar chamber 11 disposed at the opposite side of the spaced columns, the waste gas being thus led past the air-cooled tiles until its heat has been given up as fully as possible, and it is finally discharged through a suitable waste flue 12 indicated at the right in Fig. 1.

Since the space, at the sides of the recuperator which are parallel to the direction of motion of the waste gas therethrough, ordinarily need not be utilized to provide air or gas passages, it is usually possible to support such sides firmly by means of masonry walls 13 and 14 which may also extend entirely around the recuperator, but the walls 15 and 16 are spaced from the corresponding sides 17 and 18 of the recuperator to provide the chambers 10 and 11 above-mentioned.

In order to brace properly the tiles and the several columns 2 against loosening towards the sides 17 and 18 above-mentioned of the recuperator, there are provided bracing members 19 and 20 respectively within the chambers 10 and 11, which bracing mem-

bers bear against the sides of the end tiles in the respective columns 2, and serve to retain them in proper position. As is shown more clearly in Fig. 2, such bracing members 19 and 20, which preferably are in the form of continuous vertical masonry partitions extending the full height of chambers 10 and 11, divide such chambers into a plurality of vertical subdivisions, but do not 5 obstruct portions of the chambers 10 and 11 which are opposite the waste gas conduits 8, and thus free passage is afforded between the waste gas conduits 8, which are respectively between adjacent columns 2 of 10 tiles. The waste gases, therefore, may pass freely through the recuperator to the exhaust flue 12, through any one of the series of waste gas passages which are in the same vertical plane. 15

20 In order to cause the waste gases to reverse their direction of motion one or more times in passing through conduits 8, there are provided baffle plates 21 and 22 which in the present embodiment extend across 25 the chamber 10 and subdivide it into upper and lower sections. The waste gases in most instances travel through two or more of the horizontal conduits 8 "in parallel" and the recuperator preferably embodies means to 30 distribute the gas evenly between such passages. This may be accomplished in the end chambers 10 and 11, the chamber 10 in the present embodiment having a deflecting member 29 extending thereinto from the 35 wall 16. As the waste gases pass into the chamber 10 from the intake flue 9, their velocity tends to carry the major fraction thereof down to the lower of the two horizontal conduits 8 through which the waste 40 gases next pass, but the deflector 29 serves to restrict the passage of the gas into such lower conduits 8 sufficiently to cause a proper amount of the gas to flow through the uppermost horizontal conduit. In the 45 same way the waste gas passing downwardly through end chamber 11 tends to pass most readily through the horizontal conduit 8 which is next above baffle plate 22, and a deflecting member also is preferably 50 provided in this chamber. In the present form of the invention, the end wall 15, adjacent chamber 11 is provided with a projecting portion 30 which serves a function similar to that of member 29 previously 55 described.

60 The chambers 10 or 11 may be utilized to accommodate means for regulating the draft of the waste gases passing through the conduits 8. In the present instance this is accomplished in the chamber 10 by providing dampers 23 cooperating with holes 24 in each of the baffle plates 22, the baffle plates 21 and 22 being supported in proper position between the bracing or retaining members 19 previously described, and the damp-

ers 23 being accessible through suitable doors 25. Thus the flow of the waste gases through any one of the series of waste gas passages which are in the same vertical plane, may be regulated by adjustment of 70 the corresponding damper 23 through door 25 to equalize draft conditions throughout the recuperator, as well, as to regulate the total flow of waste gases therethrough.

75 The above draft regulation is particularly useful where the intake flue 9, or exhaust flue 12, is non-symmetrical with the waste gas passages, thus tending to localize the flow of such gases through the recuperator.

80 In recuperators of large size wherein many parallel columns 2 are employed, in some instances the number required of the dampers 23 is reduced, by providing openings 28 in one or more of the bracing members 19 whereby waste gas entering the chamber 10 through certain of the horizontal waste gas conduits 8, may pass through such openings 28 and down through a damper-controlled opening 24 which serves for several of the waste gas conduits. For 85 example, as shown in Fig. 2, the dampers 23 and their openings 24 are provided in connection with the first, third and fifth conduits 8, counting from the bottom of the figure, while openings 28 are provided in the second and third bracing members 19 from the bottom of the figure, whereby the waste gas passing through the second and fourth waste gas conduits, may pass through such openings 28 and down through 90 the damper-controlled opening 24 which is provided in connection with the third waste gas conduit. Thus the necessity is avoided of providing holes 24 and dampers 23 in connection with the second and fourth waste gas conduits, as shown in Fig. 2, and it will be obvious that the number of openings 28 employed may be suited to the requirements 95 of each particular installation.

100 A plurality of cleaning openings 26, having suitable removable closures indicated conventionally at 27, are provided in the wall 16 of the masonry work surrounding the recuperator, in line with each of the waste gas conduits 8, and at all different levels of the horizontal plates 7. Thus the retaining members 19 do not obstruct the cleaning of the recuperator from ash or dust deposited on the plates 7, since a hoe or other desired implement may be inserted through the openings 26 between such bracing members, in any desired portion of the recuperator.

110 It will thus be seen that the recuperator is held against loosening or shifting transversely of the columns 2, by means of the walls 13 and 14 in combination with the horizontal plates 7 which extend between adjacent columns and serve to maintain the 115 same in proper position. The bracing mem- 120 bers 19 are held against shifting transversely of the columns 2, by means of the walls 13 and 14 in combination with the horizontal plates 7 which extend between adjacent columns and serve to maintain the 125 same in proper position. The bracing mem-

bers 19 and 20 which, as cited above, preferably extend entirely across the chambers 10 and 11 to rest against walls 15 and 16, prevent the columns from loosening or shifting in a direction parallel to their length.

While a specific embodiment of the invention has been described, it will be obvious that many changes may be made there-
10 in, without departing from its spirit, as defined in the following claims.

I claim:

1. A recuperator structure comprising tiles having substantially vertical air pas-
15 sages therein, the tiles being built into parallel spaced columns, substantially horizontal plates extending between adjacent columns to provide waste gas conduits extending across the recuperator from side to
20 side, chambers disposed respectively at said above-mentioned sides of the recuperator and in communication with said conduits, bracing members extending between the outer walls of said chambers and the outer
25 sides of the end tiles of the several re-
spective columns, and substantially horizontal baffle plates extending across one of said chambers and supported by said bracing
30 members to divide said chamber into upper and lower sections, a draft regulator being provided between an adjacent pair of bracing members in one of said chambers, and one of said bracing members be-
35 ing provided with an opening affording a communication between the portions of the chamber on opposite sides thereof, whereby said draft regulator may serve to control the draft in both such portions of the
40 chamber.

2. A recuperator structure comprising tiles having substantially vertical air pas-
45 sages therein, the tiles being built into parallel spaced columns, substantially horizontal plates extending between adjacent col-
50 umns to provide waste gas conduits ex-
tending across the recuperator from side to side, chambers disposed respectively at said above-mentioned sides of the recuperator and in communication with said conduits, bracing members extending between the
55 outer walls of said chambers and the outer sides of the end tiles of the several respec-
tive columns, and substantially horizontal baffle plates extending across one of said chambers and supported by said bracing
60 members to divide said chamber into upper and lower sections, dampers being provided in connection with said baffle plates to per-
65 mit regulation of the draft in the waste
70 gas conduits.

3. A recuperator structure comprising tiles having substantially vertical air pas-

sages therein, the tiles being built into parallel spaced columns, substantially horizontal plates extending between adjacent col-
65 umns to provide waste gas conduits ex-
tending across the recuperator from side to side, chambers disposed respectively at said above-mentioned sides of the recuperator and in communication with said conduits, bracing members extending between the
70 outer walls of said chambers and the outer sides of the end tiles of the several respec-
tive columns, and substantially horizontal baffle plates extending across one of said chambers and supported by said bracing
75 members to divide said chamber into upper and lower sections, a draft regulator being provided between an adjacent pair of bracing members in one of said chambers, and one of said bracing members be-
80 ing provided with an opening affording a communication between the portions of the chamber on opposite sides thereof, whereby said draft regulator may serve to control the draft in both such portions of the
85 chamber.

4. A recuperator structure comprising tiles having substantially vertical air pas-
90 sages therein, such tiles being built into parallel spaced columns, substantially horizontal plates extending between adjacent col-
95 umns to provide waste gas conduits extending across the recuperator from side to side, means for conducting waste gas in parallel through a plurality of horizontal waste gas
100 conduits at different levels, and means for causing even distribution of the gas between the conduits through which its passes in parallel.

5. A recuperator structure comprising tiles having substantially vertical air pas-
105 sages therein, such tiles being built into parallel spaced columns, substantially horizontal plates extending between adjacent col-
110 umns to provide waste gas conduits extending across the recuperator from side to side, an end chamber affording communication between waste gas conduits at different levels to permit waste gas to pass through such conduits in parallel, and a deflector in such chamber adapted to distribute the waste gas evenly between waste gas pas-
115 sages at different levels.

In testimony that I claim the foregoing, I have hereunto set my hand this 28th day of June, 1922.

CHARLES M. STEIN.
